UNITED STATES PATENT OFFICE

111,760

DESIGN FOR A RUG

Manuel Feldman, New York, N. Y.

Application July 26, 1938, Serial No. 78,738

Term of patent 3½ years

To all whom it may concern:

Be it known that I, Manuel Feldman, a citizen of the United States, residing at New York, in the city, county, and State of New York, have invented a new, original, and ornamental Design for a Rug, of which the following is a specification, reference being had to the accompanying drawing, forming part thereof, wherein the figure is a plan view of a rug showing my new design.

I claim:

The ornamental design for a rug, substantially as shown.

MANUEL FELDMAN.
